UNITED STATES PATENT OFFICE.

CHARLES C. HIMES, OF INDIANAPOLIS, INDIANA.

RADIATOR-CAP.

1,379,626.

Specification of Letters Patent. Patented May 31, 1921.

Application filed October 2, 1920. Serial No. 414,192.

To all whom it may concern:

Be it known that I, CHARLES C. HIMES, a citizen of the United States, and a resident of Indianapolis, county of Marion, and State of Indiana, have invented a certain new and useful Radiator-Cap; and I do hereby declare that the following is a full, clear, and exact description thereof, reference being had to the accompanying drawings, in which like numerals refer to like parts.

This invention relates to a radiator cap for automobiles, trucks and the like, and particularly to the means for securing said caps upon the radiator.

Wherein metal caps having laterally extending arms or mountings of various types, it has been difficult to tightly screw them on to the radiator so that the arms or mountings will be in proper position, or when the arms or mountings are adjusted in proper position, the cap is often not screwed on tightly enough, thereby permitting leakage. By means of this invention it is made possible to so adjust the threaded portion of the cap therein that it may be screwed tightly upon the radiator with the arms or mountings in their proper position.

Another feature of the invention lies in the construction of the cap, whereby a shell or the threaded portion of an old cap may be readily and quickly inserted in any metal housing and adjustably secured therein, so that the cap may be screwed tightly on the radiator with the fittings in proper position. This arrangement enables a single casting or die for the metal portion of the cap to be used for nearly all sizes of radiator openings, so that such caps may be manufactured and sold considerably cheaper than a cap specially made for the particular opening. This feature of the construction also enables the purchaser who desires a metal cap of the particular design to purchase a standard casting and fit it to his old radiator cap, which would greatly reduce the cost of having made or purchasing a cap of special size to fit his particular radiator.

Another feature of the invention is the embodiment of a lock on the periphery of the radiator cap, whereby it may be locked upon the radiator for preventing theft of the cap or the mounting thereon. Where a particularly attractive and well made cap is mounted upon the radiator with a motometer or other mounting therein, the value

thereof and the ease of removing it often results in its theft from the automobile, and it is the feature of this invention to protect the same from such theft by means of a lock. The full nature of the invention will be understood from the accompanying drawings and the following description and claims.

In the drawings, Figure 1 is a front elevation of a radiator cap with mountings, showing a central vertical cross section through said cap. Fig. 2 is a plan view looking down on said cap and radiator. Fig. 3 is a cross section through a portion of the cap showing the lock therefor. Fig. 4 is a section through a portion of the cap and radiator neck showing a modified form wherein said neck is provided with screw threads on the inside thereof. Fig. 5 is a plan view showing the locking collar mounted about the neck of the radiator. Fig. 6 is a central vertical cross section through a modified form illustrating a Ford radiator cap with an auxiliary cap adjustably mounted thereon. Fig. 7 is a plan view of the auxiliary cap.

In the drawings there is shown a radiator cap 10 adapted to be screwed upon the opening in the top of the radiator 11. Said cap is comprised of a casting or stamping embodying, integral therewith, the outwardly extending arms 12, or other mountings or fittings, such as wings, ornaments or a motometer 13, as shown herein. The casting is provided with the projections 14 extending radially inward, as shown in Fig. 2. The casting or stamping 10 may be formed and sold upon the market together with a plate 15 adapted to fit snugly within the top of the cap and engage the projections 14 so as to prevent it from turning therein. A hole or opening 16 is provided through the center of the cap and plate. The screw threads for securing the cap upon the neck of the radiator opening are provided by the metallic threaded inserts of any cap, and particularly those used with hard rubber. The hard rubber is removed from the metal insert, or metal inserts may be manufactured for this express purpose, and secured to the metal cap in the following manner:

The method of adjusting and mounting the screw threaded insert to the cap, which is one feature of this invention, is as follows. The insert 17 is first screwed on to the neck of the radiator as tightly as possible.

The plate 15, which is provided with the screw holes 18, is then placed upon the top of the insert and adjusted thereon so that the toothed periphery will engage the projections 14 and lie in the proper and desired position, as shown in Fig. 2. The insert is then marked through the holes 18 and removed from the radiator, and the plate 15 secured thereto by screws, rivets or the like in the proper position so marked. If the insert does not have a hole corresponding to 16 already formed therein, such a hole is drilled centrally thereof so as to coincide with the hole 16 through the cap and plate. 15 The bolt on the motometer 13, or any other mounting, is inserted through the hole and secured therethrough by the nut 19. If no ornament or motometer is provided, said members may be secured together in any 20 suitable manner, such as by means of an ordinary bolt 20 shown herein in dotted lines.

By means of this arrangement whenever the screw threads are tightly screwed upon 25 the neck of the radiator, the arms 12 of the radiator 14 will at all times be in proper relation with respect thereto and one single cast metal cap will serve for use on varying sized radiator necks. It is not necessary that the insert 17 fit snugly within 30 the cap, as a slight difference in size between the insert and the cap will not affect the appearance or the functioning thereof. It is also not necessary to rivet or firmly 35 secure the insert to the plate 15 as long as there are means for holding these two in their respective positions. This may be accomplished by means of pins or projections cast or stamped upon the under side 40 of the plate 15 and extending into depressions or holes made in the insert after the two are properly adjusted on the radiator. It is also immaterial as to the position of 45 the threads upon the insert and the neck of the radiator, as upon similar radiators, the screw threads are on the inside of the neck and on the outside of the cap or insert in this case. In that event, the radiator cap 10 will surround the neck of the radiator 50 which will extend between the periphery of the cap and the insert, as shown in Fig. 4.

The locking feature of the invention consists of a barrel 21 formed integral with the outer periphery of the cap and extending 55 radially outward therefrom, as shown in Fig. 3, in which is mounted a tumbler lock 22 adapted to be operated by a key 23. The tumbler lock 22 operates the bolt 24 extending directly downward so as to engage 60 between two jaws 25 formed on the neck of the radiator in any suitable manner, or mounted thereon by means of a band 26. The band and lock are so arranged that they will be in position to be properly locked 65 when the cap is screwed tightly thereon, this

position being determined by the adjustment above described.

In the modified forms shown in Figs. 6 and 7, an insert member in the form of a Ford radiator cap 17' is shown with a 70 radiator cap 14' mounted thereover for improving the appearance, affording the arms 12 for removing it, and permitting of the adjustability above described. The insert member, or Ford radiator cap 17', as is well 75 known, is provided with four upwardly extending ears 27, and in this instance the cap 14' is provided with eight corresponding recesses 28 cast in the top thereof. A central hole is bored through the member 80 17', and it is then screwed tightly on the radiator neck 21, the cap 14' is then placed over it so that the arms 12 lie in their proper position. The ears 27 will coincide with and engage in the recesses 28, and the bolt 85 20', or motometer, will then be inserted through the central hole in both cap and member and tightened up so that they will be locked together as a single cap.

The invention claimed is:

1. The combination with a radiator cap for an automobile having a mounting thereon, of means for adjustably securing said cap to said radiator, whereby said mounting will be properly positioned with respect 95 to said automobile and radiator, including a threaded insert member adapted to be screwed upon said radiator, and means for rotatably adjusting and securing said insert member within said radiator cap in 100 fixed relation thereto.

2. The combination with a radiator cap having a mounting thereon, of means for adjustably securing said cap to said radiator, whereby said mounting will be properly positioned, including a threaded insert member adapted to be screwed upon said radiator, a securing member adapted to be 105 adjustably fixed to said insert member, and means for rigidly securing said radiator 110 cap, insert member and securing member together in adjusted position.

3. The combination with a radiator cap having a mounting thereon, of means for adjustably securing said cap to said radiator, whereby said mounting will be properly positioned, including a threaded insert member adapted to be screwed upon said radiator, a securing member adapted to be secured to said insert member, means 115 120 for preventing the rotation of said insert member within said cap after being mounted therein, and means for securing said members and cap rigidly together.

4. The combination with a radiator cap 125 having a mounting thereon, of means for adjustably securing said cap to said radiator, whereby said mounting will be properly positioned, including a threaded insert member adapted to be screwed upon said ra- 130

diator, a securing member adapted to be rigidly secured to said insert member, means for adjusting and locking said cap to said securing member against rotation, means for locking said securing member to said insert member against rotation, and means for firmly securing said members and cap together. 5 the annular adjustment of said member and 20 preventing rotation with respect to said cap, means for locking said securing member to said insert member against rotation, and means for firmly securing said members and cap together. 25

5. The combination with a radiator cap 10 having a mounting thereon, of means for adjustably securing said cap to said radiator, whereby said mounting will be properly positioned, including a threaded insert member adapted to be screwed upon said radiator, a securing member adapted to be 15 adjusted to said insert member, a plurality of teeth about the periphery of said securing member adapted to register with a corresponding tooth in said cap for permitting

6. A radiator cap for an automobile, a screw threaded member mounted within said cap adapted to screw on the radiator, and detachable means for rotatably adjusting and securing said member and cap in 30 adjustable relation to each other, whereby said cap will be properly positioned with respect to said automobile and radiator after being tightly screwed thereon. 35

In witness whereof I have hereunto af- 35 fixed my signature.

CHARLES C. HIMES.
